William W. McLean

UNITED STATES PATENT OFFICE.

LESTER OHNSTEIN, OF MINNEAPOLIS, MINNESOTA.

ILLUMINATED LICENSE-NUMBER PLATE AND TAIL LIGHT.

1,418,454.

Specification of Letters Patent. Patented June 6, 1922.

Application filed March 25, 1920. Serial No. 368,653.

To all whom it may concern:

Be it known that I, LESTER OHNSTEIN, a citizen of the United States, residing at Minneapolis, in the county of Hennepin and State of Minnesota, have invented certain new and useful Improvements in Illuminated License-Number Plates and Tail Lights; and I do hereby declare the following to be a full, clear, and exact description 10 of the invention, such as will enable others skilled in the art to which it appertains to make and use the same.

My invention has for its object to provide an illuminated license number plate that will 15 serve also as a tail light; and, generally stated, the invention consists of the novel devices and combinations of devices herein-after described and defined in the claim.

The invention is illustrated in the accompanying drawings wherein like characters 20 indicate like parts throughout the several views.

Referring to the drawings:

Fig. 1 is a rear elevation showing the complete device;

Fig. 2 is a horizontal section taken on the line 2—2 of Fig. 1; and

Fig. 3 is a vertical section taken on the line 3—3 of Fig. 1.

In accordance with my invention, the license number plate 4 has its numerals and letters cut out thereof, after the manner of a stencil, so that light can pass through to produce illuminated characters. This plate 30 is preferably a metal plate of the customary type, except that its characters have, as stated, been cut out, and in practice, it would be placed adjacent to a red glass plate 5 and the two plates 4 and 5 in close contact 35 will be inserted into a flanged retaining seat 6 formed on the front portion of a box or

housing 7. The seat 6 is preferably made open at one end for the insertion of the plates 4 and 5 and is provided with a removable end channel 8 which, when applied, 45 holds the two plates in working position. The box or housing 7, at its ends, is provided with projecting clips 9 that adapt it to be properly secured to the vehicle. At the central portion of its top, the housing 7 is 50 provided with a lamp socket 10 that holds a light bulb 11 for illuminating the interior of the housing.

Green glass plates 12 are mounted in suitable holding frames 13 provided on the ends 55 of the housing and these green plates 12 afford side lights.

By this arrangement, not only are the characters of the license plate illuminated, but they are illuminated in red color, so that 60 they afford also a tail light which, of course, is required to be in red.

What I claim is:

The combination with a substantially rectangular housing having an open front and 65 having openings at each end, an electric lamp socket, a lamp therein disposed in said housing and depending from the upper side thereof, substantially at the longitudinal center, a license number plate having open 70 characters permitting the passage of light and a colored glass plate placed adjacent the said license plate, the two plates being held together and extending over the exposed face 75 of the housing, the said housing having glass plates of different color than the first mentioned plate secured in the openings in the end thereof to serve as side lights, and attaching lugs extending at each end of the housing at the rear thereof.

In testimony whereof I affix my signature:
LESTER OHNSTEIN.
